UNITED STATES PATENT OFFICE.

JAMES H. HALL, OF RUPERT, IDAHO.

PIPE-WRENCH.

1,355,470.

Specification of Letters Patent.

Patented Oct. 12, 1920.

Application filed March 6, 1920. Serial No. 363,882.

To all whom it may concern:

Be it known that I, JAMES H. HALL, a citizen of the United States, and a resident of Rupert, in the county of Minidoka and 5 State of Idaho, have invented certain new and useful Improvements in Pipe-Wrenches, of which the following is a specification.

My invention is an improvement in pipe wrenches, and has for its object to provide 10 a wrench of the character specified especially adapted for grasping cylindrical objects, wherein handle members are pivotally connected and provided with gripping heads, the heads being normally spring 15 pressed away from each other, and the wrench having releasable means for preventing movement of the heads away from each other, one of the heads having a movable gripping jaw so mounted with respect 20 to the head that when it moves in one direction with respect to the head it is moved inwardly and is moved outwardly when it moves in the other direction with respect to the head.

25 In the drawings:

Figure 1 is a side view of the improved wrench;

Fig. 2 is a longitudinal section in a horizontal plane;

30 Fig. 3 is a transverse section through the fixed jaw;

Fig. 4 is a top plan view of the relatively movable jaw;

Fig. 5 is a top plan view of the relatively 35 fixed jaw;

Fig. 6 is a plan view of the dog;

Fig. 7 is a view similar to Fig. 2 with the jaws open;

Fig. 8 is a section on the line 8—8 of 40 Fig. 7.

In the present embodiment of the invention a casing 1 is provided, of channel shape, as indicated in Figs. 1 and 2, and this casing carries at one end a head 2, which holds the 45 relatively fixed jaw of the wrench. A second channel shaped casing 3 is pivoted to the casing 1 at the end remote from the jaws, as indicated at 4. The casing 3 is of a size to fit outside the casing 1 and the casings are arranged with their channels adjacent, and the casing 3 carries a head 3^a at 50 the end adjacent to the head 2 and this head carries a relatively movable jaw.

A plate spring 5 is arranged within the 55 channels of the casings, the said spring being secured at one end to the casing 1, as

indicated at 6, and bearing at the other end against the bottom or body of the casing 3, as clearly shown in Fig. 2, and this spring acts normally to force the heads 2 and 3^a 60 away from each other.

A ratchet bar 7 is secured within the casing 1, adjacent to the head, the teeth of the ratchet bar extending approximately transverse to the direction of the length of the 65 casings, and it will be noticed that the teeth of the ratchet bar are formed on an arc whose center is the pivotal connection between the casings.

A dog is provided for coöperating with 70 the ratchet bar, the said dog consisting of portions 8 and 9 extending at approximately a right angle with respect to each other, and the dog is pivoted to the head 3^a at 10, at the junction of the arms, the portion 8 of 75 the dog extending transversely of the axes of the casings while the portion 9 is substantially parallel therewith, and this portion 9 is outside of the casing 3 and the head 3^a. 80

A plate spring 11 is secured to the body of the casing 3 at one end and bears at its other end against the end of the portion 9 of the dog, and acts normally to hold the teeth of the portion 8 of the dog in contact 85 with the teeth of the ratchet bar. It will be noticed that this portion 8 has several teeth coöperating with the ratchet teeth. The end of the portion 9 of the dog adjacent to the spring serves as a fingerpiece for releasing the dog. When this portion of the dog is pressed inwardly the teeth of the dog will be disengaged from the ratchet bar, and the spring 5 will press the heads 2 and 3^a 90 away from each other, opening the jaws 95 of the wrench.

A gripping jaw 12 is secured within the head 2, the said head having a channel adjacent to the head 3^a in which the jaw 12 is received. It will be noticed, referring to 100 Fig. 3, that the head 2 has a longitudinally extending channel 13 on its inner face, and that the jaw 12 has a rib 14 fitting within the channel. Rivets or pins 15 are passed through registering openings in the rib and 105 in the head for securing the jaw to the head.

A relatively movable jaw, indicated at 16, is mounted in the head 3^a. This jaw, as shown more particularly in Figs. 2 and 4, has two series of ball bearings 17 extending longitudinally of the outer face thereof, and engaging the body of the head 3^a. The 110

jaw has an inclined slot 18 near its inner end and near its outer face, and a screw 19 passes through the head and through the slot, the screw limiting the movement of the jaw with respect to the head.

A coil spring 20 is arranged within the slot, bearing at its inner end against the jaw and at its outer end against the screw, and the spring acts normally to press the movable jaw inwardly and to hold it in the position of Fig. 2. Because of the inclined engaging surfaces of the jaw 16 and the head 3^a it will be evident that when the jaw moves outwardly away from the handle portion of the wrench, it will be moved inwardly, while when it moves toward the handle portion of the wrench the jaw will move outwardly. The gripping jaws have teeth, as shown in Fig. 2, the teeth fitting one series within the other.

In operation, when it is desired to turn something, the dog 8 is disengaged from the ratchet teeth by pressing on the portion 9 thereof. The spring 5 now forces the heads away from each other and the object may be gripped. By gripping the handle portion of the jaws are forced together on the object, and the dog 8 prevents release. The wrench is now manipulated in the usual manner to screw or unscrew the object and the movable jaws having a slight movement with respect to the head 3^a relaxes the grip of the wrench on the pipe sufficient to permit the wrench to be moved backward to obtain a fresh grip, it being understood that the wrench is especially adapted for gripping a cylindrical object, as, for instance, pipes, rods and the like.

I claim:

40 1. A wrench of the character specified comprising a pair of handle members pivoted together at one end and having co-operating heads at the other, a spring engaging the handle members and normally 45 pressing the heads away from each other,

releasable means for preventing movement of the heads away from each other, the head of one member being channel shaped on its inner face and a movable jaw mounted in the channel to move longitudinally of the handle members, and normally spring pressed inwardly toward the handle members, said jaw and the head having co-operating inclined engaging surfaces to constrain the jaw to move inwardly when it moves away from the handle members, and ball bearings between said engaging surfaces.

2. A wrench of the character specified comprising a pair of handle members pivoted together at one end and having co-operating heads at the other, a spring engaging the handle members and normally pressing the heads away from each other, releasable means for preventing movement of the heads away from each other, the head of one member being channel shaped on its inner face and a movable jaw mounted in the channel to move longitudinally of the handle members and normally spring pressed inwardly toward the handle members, said jaw and the head having co-operating inclined engaging surfaces to constrain the jaw to move inwardly when it moves away from the handle members. 65

3. A wrench of the character specified comprising a pair of handle members pivoted together at one end and having co-operating heads at the other, a spring engaging the handle members and normally 70 pressing the heads away from each other, and releasable means for preventing movement of the heads away from each other, said means consisting of a ratchet bar secured to one member, a dog pivoted to the 75 other member and having teeth for engaging the bar and having a finger-piece for operating the dog.

JAMES H. HALL.
